Fredrik Millborn(57) **CLAIM**

The ornamental design for an earbud holder, as shown and described.

DESCRIPTION

FIG. 1 is a perspective view of a earbud holder showing my new design;

FIG. 2 is a front plan view thereof;

FIG. 3 is a back plan view thereof;

FIG. 4 is a left side plan view thereof; and,

FIG. 5 is a top plan view thereof.

The right side plan view is identical to the left side plan view, and the bottom plan view is identical to the top plan view.

1 Claim, 2 Drawing Sheets**FIG. 1**

FIG. 2

FIG. 3**FIG. 4****FIG. 5**
